(57) **CLAIM**

The ornamental design for a support ridge of blow molding panel for banquet table, chair or the like, as shown and as described.

DESCRIPTION

FIG. 1 is a front view of the first embodiment of a support ridge of blow molding panel for banquet table, chair or the like, showing my new design.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a sectional view taken along lines 7-7 in FIG. 5.

FIG. 8 is a perspective view thereof.

FIG. 9 is a front view of the second embodiment of a Support ridge of blow molding panel for banquet table, chair or the like.

FIG. 10 is a rear view thereof.

FIG. 11 is a left side view thereof.

FIG. 12 is a right side view thereof

FIG. 13 is a top view thereof.

FIG. 14 is a bottom view thereof.

FIG. 15 is a sectional view taken along lines 15-15 in FIG. 13.

FIG. 16 is a perspective view thereof.

FIG. 17 is a front view of the third embodiment of a support ridge of blow molding panel for banquet table, chair or the like.

FIG. 18 is a rear view thereof.

FIG. 19 is a left side view thereof.

FIG. 20 is a right side view thereof.

FIG. 21 is a top view thereof.

FIG. 22 is a bottom view thereof.

FIG. 23 is a sectional view taken along lines 23-23 in FIG. 21; and,

FIG. 24 is a perspective view thereof.
